[57] CLAIM

The ornamental design for an aerosol dispenser for fragrance, as shown and described.

DESCRIPTION

FIG. 1 is a perspective view of the aerosol dispenser for fragrance of my new design;

FIG. 2 is a top end plan view thereof;

FIG. 3 is a bottom end plan view thereof;

FIG. 4 is a front view thereof;

FIG. 5 is a rear view thereof;

FIG. 6 is a right side view thereof; and,

FIG. 7 is a left side view thereof.

The broken line showing of environmental structure in FIGS. 1, 3, 5 and 6 is for illustrative purposes only and forms no part of the claimed design.

FIG.1

FIG.2

FIG.3

FIG.4

FIG.5

FIG. 6

FIG. 7
